(57) **CLAIM**

The ornamental design for a file folder as shown and described.

DESCRIPTION

1. File folder

Fig. 1.1 is a front, right, and bottom side perspective view of a file folder showing the new design;

Fig. 1.2 is a front view thereof;

Fig. 1.3 is a rear view thereof;

Fig. 1.4 is a top plan view thereof;

Fig. 1.5 is a bottom plan view thereof;

Fig. 1.6 is a right side view thereof;

Fig. 1.7 is a left side view thereof;

Fig. 1.8 is a partial enlarged view of the front view of the file folder circumscribed area 1.8 in Fig. 1.2;

Fig. 1.9 is a cross-sectional view thereof taken along the line 1.9-1.9 in Fig. 1.8;

Fig. 1.10 is a partial enlarged view of the perspective view of the file folder circumscribed area 1.10 in Fig. 1.1;

Fig. 1.11 is a partial enlarged view of the top plan view of the file folder circumscribed area 1.11 in Fig. 1.4;

Fig. 1.12 is a partial enlarged view of the bottom plan view of the file folder circumscribed area 1.12 in Fig. 1.5;

Fig. 1.13 is a partial enlarged view of the right side view of the file folder circumscribed area 1.13 in Fig. 1.6;

Fig. 1.14 is a partial enlarged view of the left side view of the circumscribed area 1.14 in Fig. 1.7; and

Fig. 1.15 is a partial enlarged view of the cross-sectional view of the file folder circumscribed area 1.15 in Fig. 1.9;

The dashed broken lines are included to show a portion of the claimed design and represent environmental structure but form no part of the claimed design; the dash-dot-dash broken lines are included to show only the bounds of the claimed design but form no part of the claimed design; and the dot-dot-dash broken lines are included to show the bounds of the enlarged views but form no part of the claimed design.

1 Claim, 15 Drawing Sheets
